LOOM SHUTTLE

Jean B. Daudelin, Fall River, Mass., and Rudolph J. Messier, East Providence, R. I., assignors to Daudelin and Messier Company, Incorporated, East Providence, R. I., a corporation of Rhode Island

Application April 13, 1944, Serial No. 530,820

5 Claims. (Cl. 139—223)

This invention relates to shuttles of the type designed more particularly for use in automatic weft replenishing looms.

In such looms the bobbin is ejected from the running shuttle when the supply of filling on the former becomes depleted and a full bobbin is forced into the shuttle as the latter is boxed at one end of its flight. Immediately after this operation has been completed, the shuttle starts on its next flight through the shed, and during this flight and at the beginning of the next one, the shuttle must automatically thread itself. The present invention aims to devise a threading device for performing this function with a high degree of certainty.

In our earlier Patent No. 2,333,413 we have shown, described and claimed a shuttle threading means which has proved very satisfactory in service. In this construction, however, some of the parts that engage and guide the thread both during the threading operation and also thereafter, are made of wire, and it has happened that the operators in the mills where these shuttles were in use have bent these wire parts apparently for experimental purposes of their own. The result practically always has been to put the threading device out of commission. It is one of the objects of this invention, therefore, to devise a shuttle threading device having the operating advantages of the construction shown in said patent, but in which this temptation to change the adjustment or relationship of the parts and the opportunity for doing so will be eliminated.

While, as above stated, the device shown in our earlier patent has proven in practice to be very satisfactory, nevertheless experiments made for the deliberate purpose of developing mistthreading or unthreading have indicated that this result might occur under some conditions rather rarely met in practice. Therefore, a further object of this invention has been to improve and perfect the construction shown in our patent above identified with a view to making it even more secure against the possibility of mistthreading or unthreading.

In the shuttle shown in said patent there is a tendency for the lint and fly to collect in the threading slot where it may interfere with the automatic threading-up action. This is common in automatic or self-threading shuttles. It is one of the objects of this invention, however, to devise a construction in which this tendency will be minimized, and in which, if such an accumulation does occur, it can be very easily and quickly removed.

The nature of the invention will be readily understood from the following description when read in connection with the accompanying drawing, and the novel features will be particularly pointed out in the appended claims.

In the drawing,

Fig. 1 is a plan view of one end portion of a shuttle equipped with a threading device embodying features of this invention;

10 Fig. 2 is a side elevation of the parts shown in Fig. 1;

Figs. 3 and 4 are transverse, sectional views through the shuttle taken substantially on the lines 3—3 and 4—4, respectively, Fig. 1;

15 Fig. 5 is a front end view of the threading device per se;

Fig. 6 is a plan view of the two sections of the threading device when laid open; and

20 Fig. 7 is an angular view of the rearward end portion of one of the parts or sections of the threading device.

Referring first to Figs. 1 and 2, the forward end of a shuttle body is there shown at 2, this body customarily being made of wood and equipped 25 with a metal tip 3. In this body is a bobbin chamber 4 for the reception of the usual filling bobbin 5. Also, as is customary in these shuttles, the body is provided with a diagonal slot 6 for guiding the yarn during the threading up operation into a laterally disposed delivery eye 7 in which a yarn guiding device 8 is mounted. As shown, this device is of a common pigtail variety.

The threading device provided by this invention comprises right and left blocks indicated at 35 A and B, respectively. These are made of any rigid and preferably non-corrosive material, such as brass, aluminum alloys, plastics, or the like. In side elevation they are roughly of rectangular form and each is provided with a flat vertical outer surface, as shown in Figs. 3, 4 and 5, a flat lower edge, and also with a longitudinal outer shoulder near its upper edge, as shown at a and b in Fig. 4, to rest on complementary shoulders provided at the upper edge of the slot c formed 40 in the shuttle body at the forward end of the bobbin chamber to receive the threading device.

The inner lateral surfaces of these two blocks are provided with parts fitting one within the other, the fit between certain of these parts being 50 sufficiently tight to position them properly with reference to each other, but the surfaces of other parts are spaced so as to cooperate in providing a tortuous, approximately vertical threading slot between them for the passage downwardly of the 55 yarn into its running position in the device. As

best shown in Figs. 5 and 6, this shaping of the inner surfaces of the two blocks includes the formation of a curved channel *e*, Fig. 5, in the block *A*, the rib *d* of block *B* fitting snugly in this channel for a considerable part of the length of the device.

Also, this block *A* is provided with a longitudinal upper edge *g* extending for practically its entire length, except where interrupted by the notch *f*, and terminating at its forward end in a nose piece *10*. From this nose piece the outer and lower surfaces slope backwardly and downwardly into a diagonal slot *11*, Fig. 6, which leads into an opening *12* that registers with the delivery eye *7*. The slot *11* also registers with the slot *6* in

the shuttle.

The other block *B* is provided with a groove *f* extending its entire length in which the edge *9* of the block *A* is positioned when the parts are assembled, as shown in Figs. 3, 4 and 5, but the extreme upper edge *14* of the block *B* overlies and projects laterally beyond the upper edge *9* of the block *A* for a considerable distance, as will be evident from an inspection of said figures. Block *A* also preferably includes a lateral extension *15*, Figs. 1, 2 and 5, which is set into the shuttle just above the forward section of the diagonal threading slots *6* and takes the place of the wood normally occupying this position. This extension may or may not be used, as desired, but we consider it preferable because it replaces a section of wood that is somewhat weakened by the very nature of its shape. When this part *15* is used, its lower surface forms a part of the upper wall of the diagonal slot *6*.

Near the rearward end of the block *B* the enlargement corresponding to the rib *d* is partly cut away, as might be done, for example, by drilling a hole *16*, Figs. 3, 6 and 7, into it from its rearward end. The walls left by such an operation, however, are further cut away so as to provide a downwardly curved horn or guard *17* and a lip *18* curved upwardly toward said horn, leaving a free space between these members at one side only of the hole.

The result of shaping these parts, as above described, is to provide the tortuous threading slot above referred to between the two blocks and to form what, in effect, is an approximately circular guiding eye in line with the bobbin axis and consisting of portions of the surfaces of the grooves *16* and *20*. The latter is made in the rear edge of the block *A*, as shown in Figs. 3 and 6.

This device is secured in place by two bolts *21* and *22* which pass through holes formed in the parts *A* and *B* to receive them, and both the heads and the nuts of these bolts are embedded in the wood of the shuttle body. A hole *23*, Fig. 7, also is formed in the part *B* to receive the shank of the guide *8* and other holes are provided to receive an upright pin *24*, Fig. 4, and a horizontal pin *25*, the latter being positioned behind the former and the two cooperating to guide the yarn in its running position. The horizontal pin *25* is positioned close to the guard or horn *17*, immediately in front of it, so that these two parts determine very accurately the position of the thread at the rear end of the device. These pins preferably have either vitreous or highly polished surfaces so that they offer very little resistance to the travel of the yarn.

When the shuttle is in actual use and the bobbin change has just been made, the end of the yarn from the new bobbin is anchored in a part of the magazine so that when the shuttle *2*, Fig. 1,

starts on its flight toward the left, the yarn running from the bobbin is guided approximately along the edge *14* and the groove *26* formed in the shuttle body. This groove registers with the upper edge of the threading slot in the threading device, and in order to guide the yarn more effectively into this slot, the upper rearward surfaces of the blocks are bevelled to form a V-shaped guide at the intake or receiving end of the device, as clearly illustrated in Fig. 1. Note that the edges *9* and *14* lie approximately in the vertical plane of the bobbin axis which also runs through the shuttle tip *3*. The tension on the yarn as it unwinds from the bobbin *5* draws it down through the tortuous threading slot above referred to, the yarn passing around the edge *14*, Figs. 3 and 5, during this movement and then being deflected toward the left (Fig. 3) around the edge *9* and an instant later around the guard *17*. As will be evident from an inspection of Figs. 3 and 6, this guard or horn lies immediately in front of the flange *20*, Fig. 6, so that the yarn must make a fairly sharp bend as it slides around the horn and into the eye *16* of the threading slot. The lower surface of the lip *18* lies in contact with a surface of complementary shape on the part *A*, as shown in Fig. 6 at *18''* so that the thread cannot get around it.

The foregoing operations take place during the first flight of the shuttle, but when it starts on its return flight the yarn passes under the nose *10*, Figs. 1 and 6, of the part *A*; slides backwardly and downwardly through the slot *11* and the registering slot *6*, Figs. 1 and 2, in the shuttle body, and subsequently slips over the hump in the guide *8* and into the delivery eye *7*.

At this time the threading operation has been completed, and thereafter the yarn travels through the eye *16*; runs over the pin *25*, Fig. 4; makes a right-angle turn around the pin *24*; and runs out through the delivery eye *7*.

There is always some ballooning of the yarn as it passes over the tip of the bobbin, and this is true whether the wind is right-hand or left-hand. In this arrangement, however, any tendency of such a balloon to run out through the threading device is effectually prevented by the cooperative relationship of the flange *20* and its relation to the curved part *20*, Figs. 3 and 6, of the eye, and particularly to the guard *17* and lip *18*, Figs. 3 and 7. Both the latter lie as close to the inner surface of the flange as is possible without interfering with the threading operation, and they make it practically impossible for either a right or left-hand balloon to unthread the shuttle. Note that the gap or lateral space provided between the upper edge of the lip *18* and the lower end of the guard *17* is very narrow, and that this space is overlapped immediately behind these members by the flange *20*. Consequently, it is an extremely difficult matter for a balloon formed in the thread, once the latter has arrived in its running position, to escape these cooperating parts *17*, *18* and *20*.

There is also a tendency for a shuttle to mis-thread or unthread, due to looping out when it starts backwardly in a direction toward the magazine end of the loom, but that is prevented in this construction by the overlap of the edge *14* of the block *B* over the edge *9* of the block *A*; the further fact that the nose piece *10*, Figs. 5 and 6, of the latter lies under the forward end of the flange *14*, Fig. 1, where the latter is curved down to guide the yarn into the threading slot, and also by the fact that this nose piece lies be-

hind the wood at the left-hand side of the groove 26. The latter is undercut, as shown at 9, Figs. 1 and 2, to provide ample space for the yarn to go into the threading slot, but it is practically impossible for a loop moving backward not to be deflected by the nose piece 10 into the slot 6.

The yarn guiding edges 9 and 14 of the blocks A and B, respectively, are notched, as illustrated at f and f', Fig. 1, and they cooperate to form a slot which opens directly into an enlargement in the threading groove between the two parts A and B. This slot opens into the region where lint and fly tends to collect, and it is a simple matter, therefore, to inspect the threading device for such an accumulation, such inspection merely involving looking into the slot. If a deposit of lint and fly is found there it can often be expelled, merely by blowing into the slot, but, in any event, it can be picked out with a hook, such as a crochet hook. The internal walls of both parts A and B in the region under the slot f-f' are made substantially parallel, upright and smooth to facilitate this operation, and they are so dimensioned as to provide an intermediate chamber of substantial size through which the yarn travels from the eye 16 up to a point under the nose piece 10 during the threading operation. Later, after the shuttle has threaded up, the yarn also travels through the rearward end of this chamber in passing around the post or pin 24.

When the bobbin is changed in the shuttle, and during the initial flight of the shuttle through the shed after that change has taken place, it sometimes happens that two or three turns of yarn will sluff off the bobbin 5 simultaneously, thus producing a loop in the yarn which may prevent the device threading up properly because this action occurs while the yarn is still running through the groove 13. Such an occurrence is practically certain to prevent the ordinary threading device from functioning properly, and will produce a mispick on the return flight of the shuttle because of this fact.

In order to avoid this result a hook 26', Fig. 6, is formed at the forward end of the notch f in the block A where it lies directly under the flange of the part B at the forward end of the notch f', as shown in Fig. 1. This hook is positioned where it will catch an outward running loop formed in some such manner as that just described and, as a rule, will cause it to ravel itself out so that the threading operation will be completed in a normal manner.

The two parts A and B of the threading device have been illustrated as separate units. At present they are manufactured in this manner, and while they can be installed in the shuttle separately, as above described, and the device so assembled will work entirely satisfactorily, still we consider it preferable to weld, braze, solder, or otherwise secure these two parts together before the device is inserted in the shuttle. In such a construction the parts are permanently united, and it is practically impossible for an operator to obtain sufficient access to any of these parts inside the device to move them out of their proper relationship, one to another, without completely wrecking the article. Also, with the members so disposed, there is much less temptation for an inquisitive workman to experiment with those parts inside the device. These elements A and B may be made by the ordinary casting operation or by die casting, the latter method, of course, being preferred.

This construction is exceptionally sturdy and

substantial, can be easily installed, and when produced by the die casting method it can be manufactured relatively economically. It is capable of giving long trouble-free service. The fact that it can be used equally as well with both right and left-hand wound bobbins is an important operating advantage.

While we have herein shown and described a preferred embodiment of our invention, it will be evident that the invention is not limited to embodiment in the precise form shown.

This application is a continuation-in-part of our earlier application Ser. No. 502,408, filed September 15, 1943.

Having thus described our invention, what we desire to claim as new is:

1. A threading device for a loom shuttle having a lateral delivery eye, comprising right and left blocks having inner lateral opposed faces with parts fitting one within the other and other parts spaced apart to provide a tortuous threading slot between them for the downward passage of a thread into running position, one of said blocks having a longitudinal upper edge extending lengthwise of said slot and projecting laterally toward the second block, the latter block having a long groove in its inner face near the upper edge thereof into which said edge of the first block projects so that the upper edge of the second block overlies said projecting edge of the first block from substantially its forward end backwardly, the forward end of said underlying edge terminating in a nose piece having front and lower surfaces extending diagonally downwardly and backwardly and forming the upper wall of a slot provided in the first block and running to an aperture in the wall of said first block adapted to register with said delivery eye, said blocks having parts fitting one within the other in front of said slot to register the two blocks, one with the other.
2. A threading device for a loom shuttle having a lateral delivery eye, comprising right and left blocks having inner lateral opposed faces with parts fitting one within the other and other parts spaced apart to provide a tortuous threading slot between them for the downward passage of a thread into running position, one of said blocks having a longitudinal upper edge extending lengthwise of said slot and projecting laterally toward the second block, the latter block having a long groove in its inner face near the upper edge thereof into which said edge of the first block projects so that the upper edge of the second block overlies said projecting edge of the first block from substantially its forward end backwardly, the forward end of said underlying edge terminating in a nose piece, the rear ends of both of said blocks having grooved surfaces forming parts of said inner faces and so opposed that, together, they form a guiding eye for the incoming yarn as it enters the threading device, said overlapped upper edges of both blocks having notches formed in them, opposed to each other and cooperating to provide an aperture opening into said threading slot, whereby lint collected in the latter slot may be removed through said aperture.
3. A threading device according to preceding claim 2, in which the inner opposed lateral faces of said blocks are shaped to provide an enlargement of the threading slot immediately below said aperture and into which the latter opens.
4. A threading device for a loom shuttle comprising right and left blocks having inner lateral opposed surfaces, certain parts of which are spaced to provide a threading slot between them

for the downward passage therethrough of the thread into running position, the rear end portion of one of said blocks having a laterally extending enlargement with a hole formed therethrough, the hole extending lengthwise of the slot and its walls completely encircling the hole except for a narrow slot at the side thereof adjacent to the other block, the latter block being recessed to receive said enlargement and providing a space through which a thread can slide downwardly through the latter slot and into said hole, said second block also having a flange at its rearward end, located behind said hole in the first block, and overlapping said hole, and said flange having a curved notch formed therein overlapping the slot in said enlargement and cooperating with the walls of said hole to form a thread guiding eye at the rearward end of the block.

5. A loom shuttle provided with a bobbin chamber, a thread delivery eye at one side of the shuttle and a socket at the forward end of said chamber and at one side of said eye, in combination with a threading device positioned in said socket and comprising right and left blocks having inner lateral opposed faces with parts of one fitting in the other to relatively position the two and also having other parts spaced apart to provide a tortuous threading slot between them, both of

10 said blocks having longitudinally extending upper edges located approximately in the vertical plane of the axis of a bobbin in said chamber, one of said blocks having a groove in its inner surface into which said upper edge of the second block extends so that one of said edges overlies the other, a space being provided around said underlying edge for the passage of the thread around said edge and down into the threading slot, said blocks having parts at the rearward end thereof providing a guiding eye for the incoming yarn, said eye being located substantially in the axis of said bobbin and said underlying edge of one of said blocks terminating at its forward end in a nose piece positioned under the edge of the second block, said shuttle having a diagonal slot leading from a region just under the end of said nose piece to said delivery eye and having a groove extending forward from the upper end of said threading slot toward the front tip end of the shuttle, the main portion of the wall of the latter groove being in line with said upper edges of the threading device but said wall being undercut at and adjacent to said nose piece to provide another guiding surface for the thread approximately in line with the underlying edge of said threading device.

JEAN B. DAUDELIN,
RUDOLPH J. MESSIER.
